UNITED STATES PATENT OFFICE.

MAX HERBERT, OF NEW YORK, N. Y.

DESIGN FOR A SUPPORT FOR TRAYS OR SIMILAR ARTICLES.

51,315.

Specification for Design.

Patented Oct. 2, 1917.

Application filed June 9, 1917. Serial No. 173,886. Term of patent 3½ years.

To all whom it may concern:

Be it known that I, MAX HERBERT, a citizen of the United States, residing in the city, county, and State of New York, have invented a new, original, and ornamental Design for Supports for Trays or Similar Articles, of which the following is a specification, reference being had to the accompanying drawing, forming part thereof.

Figure 1 is a side elevation of a support for trays or similar articles, and

Fig. 2 is a plan view of the same.

My improved design consists of the representation of a number of guns arranged in a stacked position, the barrels of the guns forming a central support and the stocks forming the legs of the support.

I claim:

The ornamental design for a support for trays or similar articles, as shown and described.

MAX HERBERT.
